VOLTAGE REGULATOR

Bennett M. Leece, Cleveland, Ohio, assignor to
 The Leece-Neville Company, Cleveland, Ohio, a
 corporation of Ohio

Application December 4, 1933, Serial No. 700,813

14 Claims. (Cl. 171—229)

This invention relates generally to voltage regulators and, more specifically, to an improved form of voltage regulating means which is suitable for use with a variable speed generator such as may be employed in a vehicle lighting and battery charging system or in various other types of generating systems. The invention relates further to a vibratory voltage regulator of the general type disposed in my prior Patent 1,540,698, 10 granted June 2, 1925, but is an improvement over the device of this patent.

Heretofore, in the construction of voltage regulating devices, it has been generally the custom to construct the regulator with its various parts, 15 and particularly its regulating resistance, designed and proportioned in accordance with the characteristics and requirements of the particular generator with which the regulator is to be used. Regulators thus designed for use with particular 20 generators have been more or less limited in application to motor vehicles in the truck and bus class, but a growing demand for voltage regulators in the passenger car class of vehicles has demonstrated the need for a regulator which, within a 25 particular class of vehicles, will be more or less generally applicable to different makes and types of generators.

It is, therefore, an object of the present invention to provide an improved form of regulating 30 device, of the vibratory type, wherein a field regulating resistance is employed having a relatively high temperature coefficient so that the device will be self-adjusting and, therefore, self-accommodating to the varying characteristics of 35 the different types of generators to which the device may be applied.

Another object of the invention is to provide an improved regulator of the type mentioned embodying a resistance element and having circuit 40 connections such that the resistance regulates the field magnetization, and wherein the effective resistance value of the resistance element is dependent upon the terminal voltage of the generator.

45 A further object of this invention is to provide an improved form of voltage regulator of the vibratory contact type which embodies a field regulating resistance and wherein the effective value of such resistance is dependent upon the 50 voltage of the generator whereby the regulator is self-accommodating to various types of generators without alteration.

55 Still another object of this invention is to provide an improved form of voltage regulator of the vibratory type which is applicable, without

alteration, to various different makes of generators within a given class and which is of very compact and economical construction and capable of operating very efficiently for effectively maintaining the terminal voltage of the generator with 5 in relatively close limits and to accomplish this function with a minimum amount of sparking at the contacts.

Other objects and advantages of this invention will be apparent from the following description, 10 when taken in conjunction with the accompanying sheet of drawing, wherein

Fig. 1 is a diagram illustrating a generating system which embodies my novel regulating means.

Fig. 2 is a diagram illustrating another generating system embodying my novel regulating means.

Fig. 3 is a diagram illustrating the same system as in Fig. 1 but with the generator shown as a 20 conventional two-brush shunt machine.

Detailed reference will now be made to the accompanying drawing wherein I have illustrated improved regulating means for use with variable speed generators and which, as mentioned above, 25 may be embodied in a generating system intended for vehicle lighting and battery charging purposes, or which may be embodied in various other generating systems.

Referring first to the arrangement illustrated 30 in Fig. 1 of the drawing, it will be seen that I have shown a generator 10 to which my voltage regulating device 11 has been applied. The generator illustrated in this instance is a generator of the three-brush type having an armature 12 35 and a field winding 13, although the invention hereinafter to be described is also readily applicable to generators of the conventional two-brush type. The generator 10 is here shown as having main brushes 14 and 15, and an auxiliary or 40 third brush 16 to which one end of the field 13 is connected by the conductor 17. Load conductors 18 and 19 may be connected, respectively, to the main brushes 14 and 15 for supplying generated power for the operation of lamps 20, for 45 the charging of the storage battery 21, or for various other purposes. Suitable switch means such as a conventional reverse current cut-out of the prior art, or a simple form of switch 22 may be provided for controlling the external load 50 circuit.

The regulator itself comprises an electromagnet 23, and a vibratory armature 24 which is actuated in response to changes in the energization 55 of the electromagnet. The electromagnet 23 is

provided with a suitable magnetizable frame 25 on which the windings or coils 26 and 27 are arranged. The armature 24 may be suitably mounted on the frame 25 as by means of the 5 flexible, electrically conducting, connection 28.

The regulator 11 is also provided with pairs of cooperating contacts which are rendered effective by vibration of the armature for controlling the excitation of the field 13, in a manner to be presently explained. These contacts are here shown as comprising stationary contacts 29 and 30, and movable contacts 31 and 32 which are carried by the armature 24 for cooperation with the stationary contacts. A suitable spring, such as the tension spring 33, may be connected to the armature 24 for normally biasing the same in a direction to cause the contacts 29 and 31 to be closed. This spring is of such character, however, that when the electromagnet 23 is sufficiently energized, the armature 24 will be moved in opposition to the spring 33 to separate the contacts 29 and 31 and, in some instances, to close the contacts 30 and 32.

For varying the field excitation, I provide a 25 field regulating resistance 35 which is adapted to be intermittently connected into and short-circuited from the circuit of the field 13 by the opening and closing of the contacts 29 and 31. This resistance is also adapted to be connected, 30 alternately, into the circuit of the field 13 and an auxiliary load circuit across the main brushes of the generator, by the opening and closing of the contacts 30 and 32. Although field regulating resistances have been used heretofore as a part of 35 voltage regulating devices, the present invention contemplates the employment of a special form of field regulating resistance which, as mentioned above, has a variable resistance value and the effective value of the resistance is dependent upon 40 the terminal voltage of the generator. As will be seen from the circuit arrangements presently to be traced, the effective value of the field regulating resistance 35 is such as to automatically adapt the regulator, without alteration, to various makes of generators within a given class, and 45 thereby makes the regulating device one of more or less universal application.

In the accomplishment of the end sought, namely that of rendering the regulator universally applicable to various makes of generators, I employ as the resistance 35 an element or device having a relatively high temperature coefficient. Although various substances or various elements having this characteristic may be employed as 55 this resistance, I find that good results can be obtained by the use of a tungsten filament lamp as this resistance. Good results can also be obtained when the resistance 35 is constructed as an iron wire resistance device.

60 Reverting temporarily to the construction of the regulator 11, I wish to point out that the electromagnet 23 may be variously constructed, but in this instance I have shown the electromagnet as embodying the coils 26 and 27 which correspond respectively with the coils 21 and 22 of my above cited prior patent. The coil 26 is a voltage coil which at all times responds to the terminal voltage of the generator, and the coil 27 is a secondary or auxiliary coil. These coils are 65 arranged on the core or frame 25 in additive relation and their combined effect is to produce an extremely rapid vibration of the armature 24 to cause correspondingly rapid opening and closing of the cooperating contacts.

70 75 When the generator is first set in operation, the

contacts 29 and 31 are closed, by reason of the action of the spring 33, and the armature 24 is then connected directly to the main brush 15 by the conductor 36 so that a full flow of field current travels through the conductor 36 and the 5 armature 24 to the field 13, and then through the conductor 17 back to the third brush 16. At the same time, the voltage coil 26 responds to the terminal voltage of the generator by reason of this coil being connected across the main brushes 10 16 and 15. As seen in the drawing, one end of this coil is connected to the brush 14 through the conductors 37 and 38, and the other end of this coil is connected to the brush 15 through the conductors 39 and 36. While the contacts 29 and 15 31 remain closed the coil 27 is also energized directly from the main brushes of the generator by reason of the fact that one end of this coil is connected to the armature 24 by the conductor 40 and the other end of this coil is connected to the 20 conductor 37.

When the speed of the generator has increased to the point where the magnetization of the frame 25, by the coils 26 and 27, attracts the armature 24 and overcomes the spring 33, the contacts 29 and 25 31 are opened. The opening of these contacts does not alter the circuit for the coil 26, but does alter the circuit for the coil 27 and the circuit for the field 13. By the opening of the contacts 26 and 31 the resistance 35 is connected in series 30 with the field 13 and is also connected in series with the coil 27. The field excitation is thereby decreased and, as a result of the field magnetization being decreased, the terminal voltage of the generator is lowered. The lowering of the terminal voltage of the generator, and the increase 35 in the resistance of the circuit of the coil 27 by reason of the resistance 35 being connected thereto, decreases the magnetization of the frame 25 of the regulator to permit the contacts 29 and 31 40 to be closed by the spring 33. The resistance 35 is thereupon short-circuited out of the field circuit and out of the circuit of the coil 27, and the terminal voltage of the generator and the magnetization of the frame 25 again increase.

45 Should the operating condition of the generator become abnormal, such as when the generator is driven at a relatively high speed or when the storage battery 21 approaches a condition of full charge, the regulator 11 then operates to exercise 50 a greater regulating action on the generator. During such abnormal condition the terminal voltage of the generator is relatively high and the magnetization produced by the windings 26 and 27 is sufficient to cause the armature 24 to operate intermittently on the contacts 29 and 30 or to operate altogether on the contact 30.

When the terminal voltage of the generator has increased sufficiently to cause the contact 32 60 to engage the contact 30, the resistance 35 is connected into an auxiliary load circuit across the main brushes of the generator. This auxiliary load circuit may be traced from the brush 15 through the resistance 35 to the armature 24, and then through contacts 32 and 30 and through 65 conductor 38 to main brush 16.

It will be observed from the novel circuit arrangement illustrated, that when contacts 30 and 32 are closed the conductor 38 of the auxiliary load circuit just traced substantially short circuits the field winding 13 and also the magnet coil 27. Since the windings 13 and 27 are of a relatively high resistance as compared to the conductor 38, it will be seen that when the contacts 30 and 32 are closed most of the current will flow 75

through the low resistance path provided by the conductor 38 and little or no current will flow through the windings 13 and 27. Hence, when this condition of the regulator occurs, the windings 13 and 27 are substantially deenergized and their magnetic fields are suddenly collapsed.

The collapse of the main field of the generator causes a desired sudden drop in the terminal voltage of the machine, and the collapse of the magnetic field of the winding 27 causes a sudden decrease in the magnetization of the regulator. The drop in the terminal voltage of the generator, due to the collapse of the field flux, also causes the magnetization of the voltage coil 26 to be correspondingly reduced. This reduced magnetization of the regulator allows the spring 33 to open the contacts 30 and 32 thereby opening the short circuit and reestablishing the field circuit through the resistor 35. Because of the sudden and substantially complete deenergization of the windings 13 and 27 which occurs upon the closing of contacts 30 and 32, I find that the armature 24 is vibrated at a very high rate and that very effective voltage regulation is obtained with only a small amount of sparking at the contacts.

It will also be observed that in the case of the third brush machine illustrated in Fig. 1, the establishment of the auxiliary load circuit by the closing of the contacts 30 and 32 causes the field winding to be connected between the main brush 14 and the third brush 16. Since the latter brush is positive with respect to brush 14 there will be a tendency for a reversal of current flow through the field winding which would further accelerate the deenergization of this winding and the collapse of the field flux and thus increase the effectiveness of the regulation. Whether or not actual reversal of current takes place in the field winding will depend upon the resistance values employed, speed and load conditions and possibly other factors.

As stated above, the resistance 35 has a relatively high temperature coefficient and the effect of this on the operation of the regulator is to increase the resistance value of this element when the terminal voltage of the generator increases. Thus, when the contacts 29 and 30 are being rapidly opened and closed and the resistance 35 is thereby being intermittently connected into and short-circuited from the field circuit, and the terminal voltage of the generator tends to increase in spite of the regulation thereby produced, there will be an increased flow of current through the resistance element 35 and, because of its high temperature coefficient, its resistance value will be correspondingly increased. Such increase in the resistance value of this element amounts to inserting additional resistance into the field circuit and into the circuit of the coil 27 which affords additional regulation of the generator.

When the contacts 30 and 32 are being opened and closed, as upon the occurrence of an operating condition which requires additional voltage regulation, an auxiliary circuit is intermittently established across the main brushes, as explained above, with a portion of such circuit substantially short-circuiting the regulator winding 27 and the field winding 13. Whenever the contacts 30 and 32 close, the resistance 35 is included in the auxiliary generator circuit just mentioned and whenever they open, this resistance is inserted in the field circuit. During such time as the regulator armature is operating on the contact 29 and conditions are such that the terminal voltage of the generator is increasing, the resistance

35 will be in the field circuit for an increased period of time and its resistance value will increase because of its positive temperature coefficient.

If conditions are such that the terminal voltage continues to increase, the armature of the regulator will ultimately operate on the contact 30, but as seen from the foregoing explanation of operation, when the contact 32 first engages the contact 30 the resistance value of the element 35 will be relatively high. If the terminal voltage of the generator continues to increase after closing of contacts 30 and 32 the resistance of the element 35 will increase further because of its positive temperature coefficient. It is desirable that the element 35 have a relatively high resistance value when the contacts 30 and 32 are closed, so as to prevent a heavy flow of current through the auxiliary circuit of the generator which would otherwise cause burning of the contacts. It will be noted however that when the resistance element 35 is placed in the auxiliary circuit by the closing of contacts 30 and 32, its location in the circuit is such that it does not prevent another part of the auxiliary circuit from substantially short circuiting the regulator coil 27 and the field winding 13 as explained above.

It will thus be seen that the regulating resistance is self-adjusting as to its resistance value, and because of this feature the regulator can be applied to different makes of generators and the self-adjustment afforded by the resistance element will enable the regulator to adapt itself to efficient cooperation with the generator to which it is applied.

In Fig. 2 of the drawing I have illustrated regulating means which is generally similar to that illustrated in Fig. 1, but wherein slightly different circuit connections are employed. In the arrangement of Fig. 2 the generator 40 is a three-brush generator similar to the generator 40 of Fig. 1, and is provided with a field 41. One end of the field winding is connected to the third brush 42 and the other end is connected to the coil 43 of the regulator 44. Load conductors 45 and 46 are connected to the main brushes 47 and 48 for supplying generated current to the lamps 49, to the battery 50, or for other uses.

The regulator 44 is also provided with a voltage coil 51 which is connected across the main brushes 47 and 48, one end of the coil being connected to the brush 47 through the conductor 52, the stationary contact 53 and the conductor 54, while the other end of the coil is connected to the brush 48 through the conductors 55 and 56. The coils 43 and 51 of the regulator 44 correspond generally as to construction and function to the coils 27 and 26 of the arrangement shown in Fig. 1. A vibratory armature 58 is arranged to respond to magnetization produced by the coils 43 and 51 so that contacts 59 and 60 carried by the armature will cooperate, respectively, with stationary contacts 53 and 61. A resistance element 62, similar to the resistance element 35 of Fig. 1, is arranged with the ends thereof connected respectively to the armature 58 and the contact 61.

During low speed operation of the generator the contacts 60 and 61 are intermittently opened and closed to thereby connect the resistance 62 into and short-circuit the same out of the circuit of the field 41. During high speed operation of the generator the contacts 53 and 59 are intermittently opened and closed to thereby intermittently establish an auxiliary load circuit across the main brushes of the generator and in which

circuit is included the resistance element 62. The circuit which energizes the field 41 while the contacts 60 and 61 are open, may be traced from the main brush 48 through conductors 56 and 63, and then through resistance element 62, armature 58 and flexible connection 66 to the magnet frame 65. Since one end of the winding 43 is connected to the magnet frame 65 the circuit may be traced further through the winding 43 and 10 through the field winding 41 back to the third brush 42. Likewise, the auxiliary load circuit which is connected across the main brushes while the contacts 53 and 59 are closed, may be traced from main brush 48 through conductors 56 and 15 63, and then through resistance element 62, armature 58, and through contacts 59 and 53 and through conductor 54 back to the main brush 41.

The resistance element 62 is similar to the resistance element 35 of Fig. 1 in that this element 20 has a high temperature coefficient and, during the operation of the regulator, the resistance of this element varies to provide the correct amount of resistance necessary for efficient cooperation between the regulator and the particular generator to which the regulator has been applied. 25 Thus, during the operation of the regulating means of Fig. 2, an increase in the terminal voltage of the generator will tend to maintain the contacts 60 and 61 separated during a longer 30 period of time but, during that period, current flows through the resistance 62 since it is then in series with the field circuit, and the greater the flow of current through the resistance element the greater will be the increase in the resistance value of this element. Similarly, when 35 the speed of the generator is relatively high and there is a tendency to maintain the contacts 53 and 59 in closed relation during a longer period of time, the correspondingly higher voltage of 40 the generator will cause an increased current flow through the resistance element 62, which is then connected into the auxiliary load circuit across the main brushes, and will result in an increase in the resistance of this element. In both cases 45 the increase in the resistance of the element 62 enlarges the capacity or regulating ability of the regulator to such an extent that the terminal voltage of any type of generator to which the device is applied is maintained substantially constant for all operating conditions. 50

In Fig. 3 of the drawing I have shown a system which is identical with that of Fig. 1 with the exception that the generator 10' is a conventional shunt machine instead of a third brush 55 machine and has the field winding 13' thereof connected to the main brush 14'. The functioning of the system of Fig. 3 is identical with that of the system of Fig. 1 except that there is no tendency for a reversal of current in the field 60 winding.

From the accompanying drawing and foregoing description it should now be readily understood, that I have provided an improved form of voltage regulator wherein the regulating resistance element is a resistance having a high temperature coefficient, and that this characteristic of the resistance element causes a variation in the effective value of the resistance as changes occur in the operating condition of the generator. This 65 self-adjustment of the resistance value of the element enables the regulator to automatically accommodate itself to the characteristics of the particular generator to which the regulator is applied and, by reason of this automatic self- 70 adjustment, my improved voltage regulator is uni- 75

versally applicable to various makes of generators within a given class without need for alteration of the regulator or any of its parts.

While I have illustrated and described my improved regulating means in a detailed manner, it 5 will be understood, of course, that I do not intend to be limited to the precise arrangements of parts and circuit connections illustrated and described, but regard my invention as including such changes and modifications as do not involve 10 a departure from the spirit of the invention and the scope of the appended claims.

Having thus described my invention, I claim:

1. In combination, a generator having a shunt field winding, a regulator comprising a magnet 15 having a coil responsive to the terminal voltage of the generator and a second coil in series with the field winding, a vibratory member adapted to be actuated by the magnet, a pair of contacts in the field circuit and adapted to be intermittently closed and opened by vibration of said member, a resistance element having its respective ends electrically connected with the contacts of said pair whereby opening of the contacts connects the resistance element in series with the field 25 and with said second coil and closing of the contacts short-circuits the resistance, a third contact with which one contact of said pair has vibratory cooperation, and circuit connections whereby engagement of said one contact and said third contact connects said resistance element in a circuit 30 across the terminals of the generator with a portion of the latter circuit in parallel with the field winding.

2. In combination, a generator having a shunt field winding, a regulator comprising a magnet having a coil responsive to the terminal voltage of the generator and a second coil in series with the field winding, a vibratory member adapted to be actuated by the magnet, a pair of contacts 40 in the field circuit and adapted to be intermittently closed and opened by vibration of said member, a resistance element having its respective ends electrically connected with the contacts of said pair whereby opening of the contacts connects the resistance element in series with the field and with said second coil and closing of the contacts short-circuits the resistance, a third contact with which one contact of said pair has vibratory cooperation, and circuit connections 45 whereby engagement of said one contact and said third contact connects said resistance element in a circuit across the terminals of the generator, said resistance element having a high positive temperature coefficient whereby its resistance 50 value increases with an increase in the terminal voltage of the generator.

3. In combination, a generator having a field winding, a regulator comprising a magnet having energizing coils and a vibratory member adapted 6 to be actuated by the magnet, a circuit for the field winding including a resistor, a pair of contacts adapted to be operated by the vibratory member for intermittently short-circuiting said resistor out of the field circuit during one condition of operation of the generator, said magnet coils including a voltage coil and a coil additive 65 to the voltage coil, a second pair of contacts adapted to be operated by the vibratory member during another operating condition of the generator, and circuit connections controlled by the second pair of contacts for substantially short circuiting said field winding and said additive coil. 70

4. In combination, a generator having a field 75

winding, a regulator comprising a magnet having energizing coils and a vibratory member adapted to be actuated by the magnet, a circuit for the field winding including a resistor, a pair of contacts adapted to be operated by the vibratory member for intermittently short-circuiting said resistor out of the field circuit during one condition of operation of the generator, said magnet coils including a voltage coil and a coil additive to the voltage coil, a second pair of contacts adapted to be operated by the vibratory member during another operating condition of the generator, and circuit connections controlled by the second pair of contacts for connecting said resistor into an auxiliary load circuit across the generator with a part of said auxiliary load circuit substantially short circuiting said field winding and said additive coil.

5. In combination, a generator having a field winding, a regulator comprising a magnet having energizing coils and a vibratory member adapted to be actuated by the magnet, a circuit for the field winding including a resistor, a pair of contacts adapted to be operated by the vibratory member for intermittently short-circuiting said resistor out of the field circuit during one condition of operation of the generator, said magnet coils including a voltage coil and a coil additive to the voltage coil, a second pair of contacts adapted to be operated by the vibratory member during another operating condition of the generator, and circuit connections controlled by the second pair of contacts for substantially short circuiting said field winding and said additive coil, said resistor having a relatively high positive temperature coefficient characteristic.

6. In combination, a generator having a field winding, a regulator comprising a magnet having energizing coils and a vibratory member adapted to be actuated by the magnet, a circuit for the field winding including a resistor, a pair of contacts adapted to be operated by the vibratory member for intermittently short-circuiting said resistor out of the field circuit during one condition of operation of the generator, said magnet coils including a voltage coil and a coil additive to the voltage coil, a second pair of contacts adapted to be operated by the vibratory member during another operating condition of the generator, and circuit connections controlled by the second pair of contacts for connecting said resistor into an auxiliary load circuit across the generator with a part of said auxiliary load circuit substantially short circuiting said field winding and said additive coil, said resistor having a relatively high positive temperature coefficient characteristic.

7. In combination, a generator having a field winding, said generator also having a pair of main brushes and a third brush to which the inner end of the field winding is connected, a regulator comprising a magnet having energizing coils and a vibratory member adapted to be actuated by the magnet, said energizing coils including a voltage coil and a coil additive to the voltage coil, means connecting the outer end of said field winding with one of said main brushes including a resistor, a pair of contacts adapted to be operated by the vibratory member for intermittently short circuiting said resistor out of the field circuit during one condition of operation of the generator, a second pair of contacts adapted to be operated by said vibratory member during another operating condition of the generator, and circuit connections controlled by the second pair of contacts for intermittently

connecting said resistor into an auxiliary load circuit across the main brushes with a portion of such load circuit short circuiting said additive coil and connecting the outer end of the field winding with the other of said main brushes. 5

8. In combination, a generator having a field winding, said generator also having a pair of main brushes and a third brush to which the inner end of the field winding is connected, a regulator comprising a magnet having energizing coils and a vibratory member adapted to be actuated by the magnet, said energizing coils including a voltage coil and a coil additive to the voltage coil, means connecting the outer end of said field winding with one of said main brushes including a resistor, a pair of contacts adapted to be operated by the vibratory member for intermittently short circuiting said resistor out of the field circuit during one condition of operation of the generator, a second pair of contacts adapted to be operated by said vibratory member during another operating condition of the generator, and circuit connections controlled by the second pair of contacts for intermittently connecting said resistor into an auxiliary load circuit across the main brushes with a portion of such load circuit short circuiting said additive coil and connecting the outer end of the field winding with the other of said main brushes, said resistor having a relatively high positive temperature coefficient characteristic. 15

9. In combination, a generator having a field winding, said generator also having a pair of main brushes and a third brush to which the inner end of the field winding is connected, a regulator comprising a magnet having energizing coils and a vibratory member adapted to be actuated by the magnet, said energizing coils including a voltage coil and a coil additive to the voltage coil, a pair of contacts between which said vibratory member is operable, a spring biasing said vibratory member toward one contact of said pair, said one contact being connected with one of said main brushes, said field winding having the outer end thereof electrically connected with said vibratory member, a resistor electrically connected with said one main brush and with said vibratory member, one end of said voltage coil being electrically connected with said one brush and one end of said additive coil being electrically connected with said vibratory member, and means electrically connecting the other contact of said pair and the other ends of said magnet coils with the other of said main brushes. 40 45

10. In combination, a generator having a field winding, a regulator comprising a magnet having energizing coils and a vibratory member adapted to be actuated by the magnet, a circuit for the field winding including a resistor, a pair of contacts adapted to be closed by the vibratory member for short-circuiting said resistor out of the field circuit, said magnet coils including a voltage coil and an auxiliary coil, a second pair of contacts adapted to be operated by the vibratory member, and circuit connections controlled by the second pair of contacts for substantially short-circuiting said field winding and said auxiliary coil. 55 60

11. In combination, a generator having a field winding, a regulator comprising a magnet having energizing coils and a vibratory member adapted to be actuated by the magnet, a circuit for the field winding including a resistor, a pair of contacts adapted to be closed by the vibratory member for intermittently short-circuiting said re- 70 75

sistor out of the field circuit, said magnet coils including a voltage coil and an auxiliary coil, a second pair of contacts adapted to be operated by the vibratory member, and circuit connections controlled by the second pair of contacts for connecting said resistor into an auxiliary load circuit across the generator with a part of said auxiliary load circuit substantially short-circuiting said field winding and said auxiliary coil.

10 12. In combination, a generator having a field winding, a regulator comprising a magnet having energizing coils and a vibratory member adapted to be actuated by the magnet, a pair of contacts adapted to be opened and closed by operation of the vibratory member, a circuit for the field winding including said pair of contacts, said magnet coils including a voltage coil and an auxiliary coil, a second pair of contacts adapted to be opened and closed by operation of said vibratory member, and circuit connections controlled by said second pair of contacts whereby closing of the latter causes the field winding to be substantially deenergized and one of said magnet coils to be short-circuited.

15 13. In combination, a generator having brushes and a field winding, a regulator comprising a magnet having energizing coils and a vibratory member adapted to be actuated by the magnet, a pair of contacts adapted to be opened and closed by operation of the vibratory member, a circuit for the field winding including said pair of contacts, said magnet coils including a voltage coil and an auxiliary coil, a second pair of contacts adapted to be opened and closed by operation of said vibratory member, and circuit connections controlled by said second pair of contacts whereby closing of the latter causes the field winding to be substantially deenergized and one of said magnet coils to be short-circuited.

20 14. In combination, a generator having a field winding, a regulator comprising a magnet having energizing coils and a vibratory member adapted to be actuated by the magnet, a circuit for the field winding including a resistor, a pair of contacts adapted to be closed by the vibratory member for intermittently short-circuiting said resistor out of the field circuit, said magnet coils including a voltage coil and an auxiliary coil, a second pair of contacts adapted to be operated by the vibratory member, and circuit connections controlled by the second pair of contacts for connecting said resistor into an auxiliary circuit across the generator with a portion of such auxiliary circuit in shunt relation to the field winding circuit, said resistor having a relatively high positive temperature co-efficient such that its resistance value is self-adjusting and is relatively high when connected into the auxiliary circuit by said second pair of contacts.

BENNETT M. LEECE.
